UNITED STATES PATENT OFFICE

EUGENE STAHL, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA

DESIGN FOR A BOWL OR SIMILAR ARTICLE

Application filed January 21, 1931. Serial No. 38,407. Term of patent 7 years.

To all whom it may concern:

Be it known that I, EUGENE STAHL, a citizen of the United States, residing at Moundsville, in the county of Marshall and State of West Virginia, have invented a new, original, and ornamental Design for a Bowl or Similar Article, of which the following is a specification, reference being had to the accompanying drawings, forming part thereof.

In the drawings:

Fig. 1 is a top plan view of a bowl or similar article, showing my new design; and Fig. 2 is a side elevational view thereof.

I claim:

The ornamental design for a bowl or similar article, as shown.

EUGENE STAHL.
